(57) **CLAIM**

The ornamental design for a bottle stopper with display surface, as shown and described.

DESCRIPTION

FIG. 1 is an environmental perspective view of a first embodiment of a bottle stopper with display surface showing my new design;

FIG. 2 is an environmental front elevational view with the rear view being a mirror image thereof;

FIG. 3 is an environmental right side elevational view with the left side being a mirror image thereof;

FIG. 4 is a top view thereof.

The broken line showing of the term “LOGO” in FIGS. 1 and 2, is for illustrative purposes only and forms no part of the claimed design. The broken line showing of the stopper in FIGS. 1-3 is for illustrative purposes only, merely disclosing the types of stoppers which can be used, and forms no part of the claimed design.
